CLAIM

The ornamental design for a belt buckle, as shown and described.

DESCRIPTION

FIG. 1 is a front, right and bottom perspective view of a belt buckle, showing my new design;

FIG. 2 is a front, right and bottom perspective view thereof, shown in disassembled condition;

FIG. 3 is a rear, right and bottom perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof; and,

FIG. 10 is another perspective view of the belt buckle of FIG. 1 shown in a state of use.

The broken lines in the drawings represent portions of the belt buckle and form no part of the claimed design. The broken lines shown in FIG. 10 showing portions of a strap represents environmental subject matter only and form no part of the claimed design.

1 Claim, 10 Drawing Sheets
